UNITED STATES PATENT OFFICE.

JOSEPH ROBIN-LANGLOIS, OF PARIS, FRANCE.

SUGAR-REFINING APPARATUS.

SPECIFICATION forming part of Letters Patent No. 705,869, dated July 29, 1902.

Application filed June 25, 1901. Serial No. 65,977. (No model.)

To all whom it may concern:

Be it known that I, JOSEPH ROBIN-LANGLOIS, a citizen of the Republic of France, and a resident of Paris, France, have invented 5 Improvements in Sugar-Refining Apparatus, of which the following is a specification.

The object of my invention is to construct an apparatus whereby to obtain in a rapid and economical way the maximum yield of 10 pure white or refined sugar from sugars of any grade.

The principal feature of my apparatus consists in the combination of successive sets of heaters, coolers, and separators so connected 15 with each other that the sugar under treatment and the treating liquid or syrup are caused to pass or travel down through the sets of apparatus together, but oppositely from one set to another, in such a manner 20 that the sugar under treatment as it passes through the successive sets of apparatus will be subjected to the action of a dissolving liquid, becoming more and more pure or less and less dense. To accomplish this object, 25 the sugar is placed in a melting-pan, melted, and then passed to a cooler, where it is crystallized. From there it is passed to a centrifugal and purged, the syrup and sugar being independently collected. The sugar is 30 then taken to a second melting-pan and again dissolved, recrystallized in a second cooler, and repurged in a second centrifugal, and so on until the purged product from the last centrifugal is a white sugar.

35 The view in the accompanying drawing is a diagram of the apparatus, partly in section.

In this apparatus there are successive sets of batteries, each composed of one or several 40 melting-pans or heaters A', (A² A³), in which the sugar is dissolved, one or more mixing-coolers B' (B² B³) underneath the heaters, and one or more centrifugal separators C' (C² C³) underneath the coolers. There is also a pre- 45 liminary set composed of a heater A, a cooler B below it, and a centrifugal C below the cooler. Each melting-pan or heater is provided with a suitable valved outlet at its bottom to permit its contents when properly dis- 50 solved to be let into the cooler B (B', &c.,) below it at the proper time for cooling and crystallization, and in like manner each cooler

has a suitable valved outlet at its bottom to permit its more or less partially-crystallized contents to be discharged into the centrifugal below to have the syrup there separated from the sugar. Means are provided for conveying the syrup from each centrifugal C³ (C² C') of the second, third, and fourth set or battery to the melting-pan or heater A² 55 (A' A) of the immediately-preceding set, as by means of a pipe e² (e' e.) This syrup is to aid in dissolving and purifying the sugar supplied to the heaters or melting-pans. To force the syrup up through the pipes, 60 suitable pumps, as b³ b² b', may be provided, taking the syrup from vessels, such as D³ D² D', which receive the syrup from the outlet-spouts c³ c² c' of the corresponding centrifugals. On the other hand, some conveying 65 means—for example, endless-belt conveyers F F' F²—are provided to carry the separated sugar from each of the first three centrifugals up into the melting-pan A' (A² A³) of the next succeeding battery. Each conveyer 70 receives the sugar from a trough f, (f' f²), into which it is delivered from the corresponding centrifugal. In this way it will be seen that the sugar is caused to travel through the successive batteries from the first battery to the 75 last—left to right in the drawing—as indicated by the full-line arrows, while the syrup is caused to travel through the same successive batteries, but from last to first, as indicated by the dotted arrows. Pure water is 80 supplied to the melting-pan A³ of the last battery through a pipe a³, for example, and as it travels through the successive batteries toward the first it gets to be a thicker and denser syrup, until finally it is discharged as 85 molasses at the outlet c from the first centrifugal C. On the other hand, as the sugar travels through the successive batteries from the first to the last it meets a dissolving and purifying liquid which is purer and purer as 90 the sugar progresses from one battery to another in its travel. Sugar which reaches the melting-pan A³ of the last battery from the centrifugal C³ has already been more or less refined by treatment in the preceding batteries, 95 and it therefore arrives at the last melting-pan almost white, to be there treated by pure water, so that when delivered at f³ from the last centrifugal the refining is complete and 100

pure white sugar is obtained. The heaters or melting-pans may be heated in any well-known way, as by steam-coils S.

I claim as my invention—

- 5 The herein-described sugar-refining apparatus, consisting of a series of successive batteries of melting-pans, coolers and centrifugals so located that the sugar passes from pan to cooler and then to the centrifugal, with
10 means connecting the successive batteries to cause dissolving liquid to travel through the

successive batteries from the last toward the first, and to cause the sugar to travel through the same batteries but from the first toward the last, as and for the purpose described. 15

In testimony whereof I have signed my name to this specification in the presence of two subscribing witnesses.

JOSEPH ROBIN-LANGLOIS.
